HEATING STOVE

Lee S. Chadwick, Shaker Heights, Ohio, assignor
to Perfection Stove Company, Cleveland, Ohio,
a corporation of Ohio

Application June 13, 1934, Serial No. 730,370

3 Claims. (Cl. 126—67)

This invention is a heating apparatus intended for heating a room or a number of adjacent communicating rooms; and its primary purpose is to provide heating apparatus that, by a simple adjustment, may be caused to function as a radiating heater or as a circulating heater, or as both, simultaneously. In other words, the invention might be termed a convertible radiating and circulating heater, and its general object is to provide a structure incorporating the features of a direct or radiating heater and a circulating heater and possessing all the advantages of both plus others peculiar to itself.

Structurally, the invention may be described in a general way as consisting of a heat radiating unit and a member spaced therefrom so as to effect between itself and said unit a duct through which air may circulate, said member comprising means for intercepting rays of heat thrown off by said unit and adjustable between effective and ineffective positions, preferably together with means for controlling the passage of air through the aforesaid duct. It follows from the foregoing that, when said heat intercepting means is in effective position, the apparatus operates as a circulating heater, and when in ineffective position, as a radiating heater.

In the specific embodiment herein disclosed, I provide a heating unit in the form of a cylindrical shell or drum enclosing a combustion chamber with oil burning means therebelow, and a casing surrounding and spaced from the heating unit and open at the top, front and sides, as well as at the bottom. Pivotaly supported on horizontal axes, within the open front and sides, are shutters, and associated with the open top is a damper arrangement for controlling the upward passage of air through the space between the heating unit and casing. The set or series of shutters at the front and at each side are adjustable independently of one another so that heat may be radiated and circulated in different directions at the same time, and by adjusting the shutters to a downward and outward inclination, at an angle of forty-five degrees, for example, they may be caused to deflect the radiant heat downwardly toward the floor. To enhance this action the inner sides of the shutters are desirably made reflective, and this is accomplished in the present preferred embodiment by coating the shutters with vitreous enamel. By reason of this controlled flexibility of operation practically any desired heat distribution may be obtained.

Objects additional to the general one above mentioned are: to provide a construction for a heater of the foregoing character that is attractive of appearance, is simple, and is relatively inexpensive; to provide a form of mounting for the aforesaid shutters that facilitates their emplacement and insures easy and satisfactory operation; to provide means for effecting simultaneous operation of all shutters associated with the open front or either of the open 10 sides of the casing; to provide a very simple contrivance, preferably frictional, for holding said shutters in any position to which they are adjusted, and to provide means for holding the dampers associated with the open top of the 15 casing against vibration.

The foregoing objects, with others which will appear as this description proceeds, are attained in the embodiment of the invention illustrated in the accompanying drawings wherein Fig. 1 is a vertical section, from front to rear, through heating apparatus constructed in accordance with the invention; Fig. 2 is a sectional plan on the line 2—2 of Fig. 1, the same being on a scale somewhat larger than that of the preceding view; Fig. 3 is a vertical section, from front to rear, through the casing of the apparatus, on the same scale as Fig. 2 and showing the shutters in closed position, the combustion chamber being omitted for clearness; Figs. 4 and 5 are sectional details, on a further enlarged scale, taken, respectively, on the lines 4—4 and 5—5 of Fig. 2; Figs. 6 and 7 are views at right angles to each other of a retaining member for the pivots at one end of the shutters of a series; Fig. 8 is a plan view of such member on a scale considerably enlarged over that of Figs. 6 and 7; Fig. 9 is a horizontal section through one of the front corners of the casing showing the pivotal mountings of adjacent front and side shutters; Figs. 10 and 11 are sections on the respective lines 10—10 and 11—11 of Fig. 9; Fig. 12 is a detail, similar to Fig. 9, showing the pivot retaining member in an ineffective position as when the parts are being assembled; Fig. 13 is a bottom plan view of the top of the casing removed and showing the dampers mounted thereon; Fig. 14 is a transverse vertical section through the top of the apparatus, the plane of section being indicated by the line 14—14 of Fig. 13; Figs. 15 and 16 are enlarged sectional details on the respective lines 15—15 and 16—16 of Fig. 13; Fig. 17 is a section on the line 17—17 of Fig. 16, and Figs. 18, 19 and 20 are details pertaining to

a modification of the friction means for holding the shutters in any adjusted position.

The casing of the apparatus is made up of corner members or posts 1 of angular formation whose lower ends rest upon the corners of a rectangular frame 2 that is supported a suitable distance above the floor by legs 3. At the front and sides, stationary panels 4 are supported by and between the upper ends of the corner posts 1, and similar panels 5 are disposed between and connected to the lower ends of said posts and extend down into and are secured to the frame 2. A wall 6 occupies the space between the posts 1 at the rear of the casing and extends from top to bottom thereof. Gussets 7 are applied to the tops of the corner posts and overlie adjacent parts of the panels 4 and 6 and are suitably attached thereto, the outer edges of the gussets being flanged and projecting a material distance beyond the outer surfaces of the posts. A top 10 surmounts the casing and is supported by the gussets 7.

The top 10 is in the nature of an open grid, having two series of slots 11 on each side of its transverse center (Figs. 13 and 14). Depending from the top along each side of each series of slots 11 is a flange 12, those adjacent the lateral edges of the top being parts of angle members whose other flanges are connected to the top by any suitable means, while those adjacent the transverse center are the flanges of a channel member whose web is engaged with the underside of the top and has a series of openings registering with openings in the top, the registering openings of the channel member and top being designated 15. Certain of said openings—those at the ends and at the longitudinal center of the channel member, according to the present embodiment—are made larger than the others, and the material of the top 10 is punched and projected downwardly through said openings and flanged outwardly therebeyond in the nature of eyelets, as indicated at 16, to secure the channel member to the top.

Dampers 17 (Figs. 13 to 17), in the form of flat plates having peripheral flanges 18, and provided with slots 19 that correspond in size and spacing with the slots 11 of the top, are supported below the top by studs or bearing members 20 that are carried by the flanges 18 of the damper and extend through slots or openings 21 in the flanges 12. As clearly shown in Figs. 16 and 17, the slots 21 are considerably wider than the diameter of the studs 20, and the studs are yieldingly held against the bottom sides of the slots by springs 22 whose body portions bear upon the tops of the studs and whose ends are formed with transverse hooks 23 that are engaged beneath the flanges 12 and embrace them closely enough to prevent lateral movement of the springs, the flanges being notched at 24 for the reception of the hooks at one end of the springs for holding the springs against longitudinal displacement. The slots 11 of the top, and 19 of the dampers, are surrounded by depending flanges 11^a and 19^a, respectively; and it will be observed that the dampers are supported with their upper surfaces out of contact with the flanges 11^a. The springs 12 are sufficiently stiff to effectively hold the dampers from being vibrated by air currents rising through the casing. The dampers are equipped with knobs 25 whose shanks project through slots 26 in the top 10, and by means of these knobs the dampers may be conveniently shifted.

The lateral and front sides of the casing have

openings defined by the corner posts 1 and the top and bottom panels 4 and 5, and within each opening is arranged a series of shutters 30. Each shutter consists of a rectangular plate that is surrounded by a flange, and suitably secured to the end portions of the flange are pivot or bearing members 33. Said members, at one end of the shutters of each series (see Fig. 2), are engaged through bearing apertures in a straight inturned flange 34 of the adjacent corner post 1, while those of the opposite end are accommodated by notches 35 in a substantially L-shaped flange 36 of the contiguous corner post 1. As may best be seen from Figs. 9 to 12, the L-shaped flange 36 provides an inwardly facing channel downwardly through which may be projected a rod-like pivot retaining member or spring 37 (Figs. 6 to 8), having humps 38 spaced apart therealong. The top end of each member 37 is offset at 39, somewhat after the fashion of a crank, effecting a shoulder 40. It is evident from the corner post appearing in Figs. 1 and 3 that the laterally turned inner edge or channel portion of the flange 36 terminates at its upper end about flush with the lower edge of the top panel 4 and at its lower end in the same relation to the upper edge of the bottom panel 5; and that the shoulder 40 of the retaining member 37 engages the upper end of said channel portion and serves as a stop to limit the downward movement of the pivot retaining member. It will also be apparent that the upwardly extended offset portion 39 of the retaining member is in a position to engage the gusset 7 thereabove and by this arrangement each member is held against upward displacement. In the installation of the shutters, the pivot or bearing members 33 at one end are projected through the bearing apertures in the straight flanges 34 of one corner post and the shutters are then swung into place to engage the pivot or bearing members 33 at their opposite ends within the notches 35 of the flanges 36, it being observed from Fig. 11 that the inner ends of said notches are reduced in width to substantially the diameter of the pivot or bearing members. The pivot retaining member 37 is next projected downwardly through the channel portion of the flange 36 in the position shown in Fig. 12 and, by means of the offset upper end 39, the member is turned to the position shown in Fig. 9, which causes the humps 38 to be swung about within the channel and force the portions of the member 37 between the humps into firm contact with the pivot or bearing members 33, the retaining member being somewhat deformed by this operation, as indicated in Fig. 11, wherefore it will be retained under tension and thus constantly impose a pressure upon the pivot or bearing members in a direction to force them into the restricted ends of the slots 35. When the pivot retaining member is in this position its offset end 39 is pressed against an adjacent part of the inner side of the post 1, as illustrated in broken lines in Fig. 9.

Arms 45 (Figs. 4 and 5) extend from the corresponding ends of the shutters 30 of each series, and the inner ends of these arms are offset laterally, as best shown in Fig. 5. A link 46 connects all arms of the shutters of a series, causing said shutters to operate in unison, and, excepting in the modification illustrated in Figs. 18 to 20 which will hereinafter be described, a tongue 47 is pivotally joined to the arm of the lowest shutter, along with the lower end of the link 46, said tongue being offset laterally intermediate its ends, as shown at 48. The section of the tongue in the 75

region of and including said offset portion is guided within a tubular member 49 that is secured, as by fastening means 50, to the flange 34 of the adjacent corner post. The tongue 47 is of resilient metal and, in the region of its offset portion 48, is somewhat compressed and placed under tension when forced into the tubular member 49. Thus a frictional means is provided for holding the shutters in any position to which they are 10 adjusted, and the adjustment may be made by grasping a knob 51 on the top shutter and swinging said shutter to the desired position, the others of the series assuming corresponding position by reason of their connection with the top shutter 15 through the arms 45 and link 46.

In the modification illustrated in Figs. 18, 19 and 20, the link 46 carries pivot members 47^a, shown as tubular and as having their inner ends internally threaded and their outer ends reduced 20 and engaged through holes in the link 46 and peened over therebeyond. The pivot members 47^a are journaled in the bearing apertures of the arms 45 of the shutters.

A bolt 48^a is screwed through next to the top bearing member 47^a, according to the arrangement selected for illustrative purposes, and a nut that is applied to its outer end, locks the bolt against unscrewing. A spring 50^a is compressed between opposed washers, one of which engages 30 the head of the bolt and the other the arm 45. By means of this spring sufficient friction is created between the arm 45 and link 46 to hold the shutters in any position to which they are adjusted. Obviously springs and bolts may be used with 35 others of the pivot members, if desired, although it has been found that one such outfit affords ample friction for holding the shutters of a series of the number shown. Also, excepting for manufacturing expedience, those pivot members with 40 which bolts, springs, etc. are not used might be solid.

Now to resume the general description:

Supported centrally within the casing, as by brackets 54 (Fig. 2), is a heating unit 55 which, according to the present embodiment, consists of a cylindrical drum 56 that encloses a combustion chamber 57 and, therebelow, a firepot 58. The latter has an annular top wall 59 (Fig. 1) that is connected to and spaced from an annulus 60 by fastening means 61, and the annulus, in turn, is connected, as by bolts 62, to a somewhat similarly shaped but larger member 63 which, with the annulus, forms the bottom wall of the combustion chamber. The member 63 has a peripheral flange that is suitably secured to the wall of the drum 56. The inner edge of the top wall 59 of the firepot 58, and the corresponding edge of the annulus 60, are turned downwardly so as to direct air entering through the slot 53, between the said top wall and annulus, downwardly into the firepot. A neck 64 projects forwardly from the firepot and surrounds a lighting and clean-out opening which is normally closed by a plug 65 having a handle 66. The forward end of the neck extends through an opening 67 in the front bottom panel 5, which opening is adapted to be covered by a closure 68 that is removably held in place by any suitable means.

The bottom of the firepot is shown as formed with a sump 69 to which fuel is delivered, by gravity, through a conduit 70, from a fuel reservoir 11, the fuel feed being of such character as will maintain a liquid level within the sump 69 slightly below the plane of the bottom wall of the firepot.

The flow of oil to the firepot is adapted to be controlled by a metering valve 72, equipped with an operating handle 73. Primary air is admitted to the firepot 58 through holes 74 in the peripheral wall thereof. The heating unit or combustion device, per se, forms no part of my present invention, and details thereof may be had by reference to Letters Patent No. 1,944,593, dated January 23, 1934, wherein it is disclosed and claimed. The fuel reservoir and control means, with their 10 associated parts, as herein generally illustrated in Fig. 1, are shown in detail in an application filed by me on March 7, 1932, bearing Serial No. 597,-168.

To light the apparatus, the closure 68 and plug 15 65 are removed and the valve 72 opened to supply fuel to the sump 69, and the oil is ignited by a lighted match, taper or piece of paper inserted through the neck 64. With the fire thus started, primary air is drawn in through the holes 74 and 20 secondary air through the slot 53, the mixture burning within the fire pot and in the combustion chamber 57 thereabove, the products escaping 25 through a flue connection 75 that joins the rear side of the drum 56 adjacent its upper end and projects through the back panel 6 of the casing.

When the shutters 30 are open, at which time the dampers 17 are desirably closed, heat will be radiated from the heating unit or combustion device through the openings in the front and 30 lateral sides of the casing, and by inclining the shutters the heat rays may be deflected downwardly toward the floor, the underneath surfaces of the shutters being preferably made reflective to enhance this action. In the present preferred 35 embodiment, this follows from the fact that the shutters, with other parts of the casing, are coated with vitreous enamel. When the shutters are closed and the dampers 17 are open, air will enter the bottom of the casing and rise through 40 the duct between the casing and the heating unit and escape through the openings 11 in the top 10, under which circumstances the apparatus will function purely as a circulating heater and will be more effective in heating remote parts 45 of the room in which the heater is located or in heating adjacent communicating rooms. When the shutters are open and the dampers closed, as above described, the apparatus will operate as a direct or radiating heater and effectively heat the region immediately in front of and at the sides of the apparatus. By adjusting the different series of shutters at different angles, various effects may be attained as, for example, the apparatus may be caused to function as a direct 50 or radiating heater immediately in front of the structure and as a circulating heater at the sides, and vice versa; and a very even distribution of heat throughout the environs of the apparatus may be accomplished by properly adjusting the 55 shutters and dampers.

Having thus described my invention, what I claim is:

1. In heating apparatus, the combination of a heat radiating unit, a casing surrounding said unit and provided with a plurality of regulable means independently adjustable for controlling the radiation of heat from different laterally spaced wall portions of said unit and for effecting with each of such wall portions as an alternative condition a passage through which air may circulate, a top for said casing having a plurality of independently regulable means for controlling the discharge of air therethrough, said last means being each located above a respective 70 75

wall portion of the unit and cooperating with the corresponding first means to control the circulation of air adjacent that wall portion.

- 5 2. In heating apparatus, the combination of a heat radiating unit, a casing surrounding said unit and provided with regulable means on different sides thereof independently adjustable for controlling the radiation of heat from the adjacent side wall portions of said unit and for effecting with each of such wall portions, as an alternative condition, a passage through which air may circulate, the top of the casing having a plurality of independently regulable means for controlling the discharge of air therethrough, said last means being each located above a respective side wall portion of the unit and cooperating with the corresponding first means to
- 10
- 15

control the circulation of air adjacent that wall portion.

3. In heating apparatus, the combination of a vertically disposed heat radiating unit, a casing surrounding said unit and provided with regulable means on opposite sides thereof independently adjustable for controlling the radiation of heat from the adjacent side wall portions of said unit and for effecting with each of such wall portions, as an alternative condition, a passage through which air may circulate, the top of the casing having two independently regulable means for controlling the discharge of air therethrough, one being located above each of the aforesaid side wall portions of the unit and cooperating with the corresponding first means to control the circulation of air through the passage below.

LEE S. CHADWICK.
